FIG. 1 is an upper perspective view of a combination snow scraper and ice chopper for rooftops in accordance with the present invention;

FIG. 2 is a rear elevation thereof;

FIG. 3 is a front elevation thereof;

FIG. 4 is a side elevation thereof;

FIG. 5 is an opposite side elevation thereof;

FIG. 6 is a top plan view thereof;

FIG. 7 is a bottom plan view thereof;

FIG. 8 is an upper perspective view of a combination snow scraper and ice chopper for rooftops in accordance with the present invention;

FIG. 9 is a rear elevation thereof;

FIG. 10 is a front elevation thereof;

FIG. 11 is a side elevation thereof;

FIG. 12 is an opposite side elevation thereof;

FIG. 13 is a top plan view thereof; and,

FIG. 14 is a bottom plan view thereof.

The areas of the combination snow scraper and ice chopper for rooftops that are shown in broken lines form no part of the claimed design.
